UNITED STATES PATENT OFFICE.

SAMUEL VAN RANSIELAER HENDRYX, OF FARMINGTON, MINN., ASSIGNOR
OF ONE-HALF TO ANDREW FINKELSON, OF NORTHFIELD, MASS.

DISPLAY-RACK FOR UMBRELLAS.

SPECIFICATION forming part of Letters Patent No. 328,487, dated October 20, 1885.

Application filed May 6, 1885. Serial No. 164,617. (No model.)

To all whom it may concern:

Be it known that I, SAMUEL VAN RANSIELAER HENDRYX, a citizen of the United States, and a resident of Farmington, in the county 5 of Dakota and State of Minnesota, have invented certain new and useful Improvements in Display-Racks for Umbrellas, of which the following is a specification.

This invention relates to frames or racks for 10 the display of parasols, umbrellas, walking-sticks, and similar goods in stores, &c.; and it consists in the construction and arrangement, as hereinafter shown and described.

Figure 1 represents a perspective view of 15 one of the racks empty; Fig. 2, a cross-sectional elevation with a number of parasols shown arranged therein.

The rack consists of ends A' A², having feet B' B², and connected by a trough-shaped section C' at the bottom and bars D' D² at the top. A short distance above the trough-shaped bottom section, C', the ends A' A² are connected by bars D³ D⁴, similar to the bars D' D², and in a line below them. A short distance below the bars D' D² the ends A' A² are connected by a trough-shaped section, C². The distance between the bars D' D² and the trough-shaped section C² is about the same as the distance between the bars D³ D⁴ and the trough-shaped bottom section, C'. The bars D' D² have cross-wires a', connecting their interior sides at regular intervals, while the bars D³ and D⁴ have similar wires, a², connecting their interior sides. The spaces between the wires 35 will be about the thickness, or a little more than the thickness, of a parasol or umbrella when closed. The sides of the trough-shaped sections C' and C² will also be connected by cross-wires a³, the space between the latter 40 being about one-half of the spaces between the wires a' a², or, in other words, there will be just twice as many wires in the trough-shaped sections as there are between the bars D' and D² and D³ and D⁴.

45 The wires in the trough-shaped sections are intended to receive the lower ends of the umbrellas or parasols E, as shown in Fig. 2, two of the parasols being thus inserted from opposite sides of the rack between each pair of 50 the wires a' a², while the lower end of each of

the parasols or umbrellas has a space to itself between each pair of the wires a³ in the trough-shaped sections. The parasols are thus held from side-play, or from being shaken about, and each parasol or umbrella can be removed 55 from and replaced in its respective position without interfering with or disturbing any of the others. Thus, when a customer is purchasing a parasol or umbrella, the one selected can be removed, examined, and replaced without 60 disturbing any of the others, or any desired number may be removed and, after inspection, replaced by the clerk at his pleasure. By this means the parasols, &c., are held in a compact position, occupying very little room, 65 while at the same time every separate article is open to inspection.

The handle of each separate parasol, &c., is distinctly shown, and as the handle is usually the first thing examined this is an additional 70 advantage.

The trough-shaped section C' is narrower than the trough-shaped section C², to give more room for the insertion of the lower set of parasols, &c., and avoiding the necessity of forming the 75 bottom of the rack wider than the top. This is a very important feature of my invention, as it enables me to display the parasols, &c., in an equally advantageous manner, while occupying less room than if the two trough-shaped sections were of the same width.

It is not necessary to the perfect operation of this invention that the trough-shaped sections should be supplied with double the number of pins of the bar-sections D' D² D³ D⁴, as 85 the trough-shaped sections may be supplied with perforations in which to insert the lower ends of the parasols or umbrellas; or under some circumstances the trough-shaped sections might be formed entirely open, and free from 90 all cross wires or divisions for the parasol or umbrella points; but I prefer the arrangement shown in the drawings, as it supports the goods in a much better shape than if the double set of wires were not present.

95 By this simple device the parasols are prevented from being soiled or torn by rough handling, or by the friction of one upon the other.

The goods are held in so compact a form 100

that they may be easily protected from dust by simply throwing a cloth over them at night, or when the racks are not in use.

Another great advantage gained by this simple arrangement is that a large number of different styles of parasols, &c., may be displayed within a very small space merely as samples, while the main stock of goods may be kept packed away in show-cases, &c., and free from injury by handling, dust, &c.

Having thus described my invention, what I claim as new is—

A display-rack for parasols, umbrellas, and the like, consisting of ends A' A², top connecting-bars, D' D², having cross-wires a' between them, trough-shaped bottom section, C', intermediate trough-shaped section, C², and intermediate bars, D³ D⁴, connecting said ends between said trough-shaped sections C' C², and having cross-wires a², said intermediate trough-shaped section being narrower than said trough-shaped section C', whereby the goods supported by said bars D³ D⁴ and wires a² will occupy less space, substantially as set forth.

20
In testimony whereof I have hereunto set my 25
hand in the presence of two subscribing witnesses.

SAMUEL VAN RANS AELAER HENDRYX.

Witnesses:

C. N. WOODWARD,

Correction in Letters Patent No. 328,487.

It is hereby certified that the residence of the assignee in Letters Patent No. 328,487, granted October 20, 1885, upon the application of Samuel Van Ransaelaer Hendryx, for an improvement in "Display Racks for Umbrellas," should have been written and printed *Northfield, Minnesota*, instead of "Northfield, Massachusetts;" and that the said Letters Patent should be read with this correction therein that the same may conform to the record of the case in the Patent Office.

Signed, countersigned, and sealed this 10th day of November, A. D. 1885.

[SEAL.]

H. L. MULDROW,
Acting Secretary of the Interior.

Countersigned:

M. V. MONTGOMERY,
Commissioner of Patents.
